LAUNDRY METHOD AND BAG

Robert A. Phair, Allendale, N. J., and William A. Schnakenberg, Hollis, N. Y., assignors to H. Kohnstamm & Co., Inc., New York, N. Y., a corporation of New York

Application May 1, 1941, Serial No. 391,292

4 Claims. (Cl. 8—137)

1

This invention relates to new and improved methods and means for washing and laundering clothes and the like, and more particularly the invention is for use in commercial laundries. The invention especially relates to a new laundry method and bag which facilitates the washing of clothes or other articles in classified lots on a more economical basis than present-day conventional practice and prevents the laundry work of a customer from becoming separated and scattered during the laundry process.

In commercial laundries, it is the usual or conventional practice to classify a customer's soiled laundry into several groups or classes of work (say three classes, more or less) in accordance with such conditions as the amount of washing required for each particular article or piece of work, the type or kind of textile weave or material and the texture thereof, such as natural textile fibers or synthetic textile fibers, etc., as well as the color thereof, whereupon each classified lot or group of work of a customer is placed in net bags, one bag for each class of said customer's work, and all the bags containing like classes of all customers' work are then placed in a washing machine having a washing liquid or bath formula mix especially graded in strength and prepared for that particular class of work making up the load or run for that washing machine.

Accordingly, present-day standards mean that the laundryman or superintendent must operate one or more washing machines for that collective lot of various customer's work representing each classification. Therefore, the number of washers in operation, with their respective washing liquids graded and prepared under a preselected formula for each class of soiled work, must at least equal the number of work classes a particular laundry adopts for its routine washing, say three classes, more or less, which means at least that many or more washers are in actual operation. Such a number of washers is required irrespective of the volume of work on hand. Otherwise, delay would ensue due to waiting for release of a washer or washers previously assigned to some other work classification.

In the event that the volume or run of work is small at one time or another, it follows under conventional practice that the washing machines do not have appropriate capacity loads and hence do not operate efficiently. This leads to such disadvantages as lack of economy in all the washing materials, to-wit, water and soap, bluing and soda, etc., and other ingredients constituting the

2

washing liquid or bath mix formula prepared in each washing machine for the particular class of work processed by that machine.

Conventional laundry washing also includes the use of standard type net bags without regard for the size mesh netting or porosity thereof, with the result that classification of the work into the bags is not made so as to conform the amount of washing required, for a particular work class, with the grade mesh or porosity of the net bags. This means that a classification of work comprising say dark color pieces requiring less washing nevertheless may be subjected to the same volume of water flow through the net bag and hence the same amount of washing as other work classes which in fact actually require maximum washing. Therefore, present practice results in over-washing and underwashing, a problem dealt with and sought to be solved by this invention.

Furthermore, the conventional classification practice is based upon the use of separate net bags which results in separating the several classes of a customer's laundry in order that same may be washed in the respective machines, thereby causing likely loss of some portion of a customer's laundry as well as requiring the further labor of subsequent handling and reassembling of the work from the several washing machines.

An object of this invention is to provide a new laundering method employing the usual work classification to which a commercial laundry is conveniently accustomed but characterized by washing several work classes in the same washing machine with one bath mix formula. Thus one washing liquid batch or bath is used for the several classifications of work. Consequently, there is a saving in labor, washing machine capacity, washing materials such as hot and cold water and ingredients used in preparing the bath mix, and likewise a saving of power and heat in the operation of a commercial laundry by following the principles of this invention.

Likewise, it is an object of the invention to provide a new laundry process or method, involving the use of pre-selected bags or other forms of containers having graded or graduated size porosity adapted and proportioned in said porosity size to the respective work classes, which results in the correct and approved amount of washing because the circulation and flow of washing liquid or bath mix formula is proportioned to a given work class in order that over-washing or underwashing may be avoided. This plan is new in the art and provides a new result.

55 A further object of this invention is to produce

a new multiple-unit net bag means or member compartmented into a combination of a plurality of pockets or receptacles of graded or graduated-size porosities or mesh-size openings for use in not only practicing the method of this invention but also for the purpose of keeping all or some of a customer's classified work together in one lot as a unit in a single combination bag member, thus rendering unnecessary the subsequent assembly of the customer's work.

With the foregoing and other objects in view, the invention has relation to the discovery and appreciation and hence the recognition of certain problems having to do with the laundering of soiled work and the provision of a new method as well as a new net bag or other form of construction, as herein described and shown in the accompanying drawing illustrative of examples of the principles of this invention presented herewith as a solution of the laundry problems in question.

Figure 1 shows several conventional separate net bags or separate laundry holders or containers of graduated porosity or mesh size for use in practicing this new method which employs present standards of work classification dealt with in a new light to accomplish the ends of this invention. A series of three bags is shown, by way of example, but any number from two up may be employed, depending upon how many classes a particular laundry may divide its soiled work preliminary to washing.

Figure 2 shows an example of a netted bag member or laundry container of multiple compartments or multiple bags having graduated porosity, in effect being the three bags of Figure 1, either joined together or integrally knitted. The composite multiple-unit bag illustrated has three net compartments or bag pockets of various size mesh openings, but this aspect of the invention contemplates the use of a bag construction having anywhere from two compartments to as many as may be desired, as explained in connection with the method of Figure 1.

The number of compartments in the multiple-unit bag (Figure 2) is to be determined by such factors as the number of work classes in vogue in a given laundry, as well as the overall size and weight, which are factors having to do with convenience in handling the bags of wash work in a laundry.

An example is taken herein, for the purpose of explaining this invention, of a commercial laundry which makes standard three selective classifications of its soiled work preliminary to the washing or processing thereof. Accordingly, the drawings show washing containers in the form of net bag means in groups of three. Thus, in conventional practice, three washing machines are employed, more machines being used by a laundry preferring four or five work classes. In effect, therefore, the present day practice requires as many washing machines, or groups of washers, in operation as there are work classes in a given laundry, and such practice is not efficient in production when there is a low run of work too small in volume to classify into efficient capacity loads for each work class washing machine.

The above example of conventional practice means that a large number of bags 1 of $\frac{1}{2}$ inch porosity mesh, or with whatever size mesh the laundry works, are placed in as many separate washing machines as there are work classes, thus necessitating the laundry superintendent to pro-

portion the strength or cleansing power of his washing liquid or bath mix formula in a machine in accordance with the class of work in the respective bags placed in that machine. In present-day practice, all the bags are either of uniform porosity or at least are not pre-selected, with the result that miscellaneous and haphazard mesh sizes are indiscriminately used, irrespective of the difference in work classes.

Accordingly, if a commercial laundry has a light day's run, without enough bags 1 containing different classes of laundry work requiring different degrees of washing to provide capacity loads in as many machines as there are work classes, the laundryman nevertheless has to operate as many washing machines as he has work classes for a given run. This invention is for the purpose of simplifying that problem and reducing the number of machines occasioned thereby. This is brought about by a new method of using the net bags, which not only reduces the number of washing machines but enables the laundryman to employ one formula of bath mix for all classes of work sorted into the separate net bags, and which also insures against over and under washing.

In accordance with the principles of this invention, and first taking up the new method, there is provided a series of laundry work containers, say net bags 1, 2 and 3 (Figure 1) having graduated size mesh or porosity graded and pre-selected to the degree and amount of washing required for the several classes of work, instead of simply employing a number of standard type or types of bags of one or uniform size mesh, or of indiscriminate or mixed size mesh, as is now used in laundries. Therefore, under this new method, the laundryman places the work class of white soiled pieces (such as white shirts, white underwear, and white flatwork, etc.) in bag 1 of large or $\frac{1}{2}$ inch porosity; the soiled work class of printed materials and dye-fast work is placed in bag 2 of medium or $\frac{1}{4}$ inch mesh; and another or third class of work comprising dark colors such as socks and colored dresses is placed in bag 3 of small mesh or about $\frac{1}{8}$ inch porosity.

The net bags shown in Figure 1 are standard or conventional bags of the kind now in general use in commercial laundries. In fact, the three bags shown are merely examples of one series of mesh-size openings now in use; a variety of mesh-sizes are stocked by suppliers and available to laundries. Thus it is to be understood that Figure 1 not only is presented merely as an example, something from which to explain the principles of this invention, but likewise the invention may be practiced with more than three bags; any number are contemplated, depending upon the number of work classes a given laundry has established for its line of customer service. Breaking the soiled work down into four classes is good practice followed by some laundries, but three classes are sufficient for the purpose of disclosing this invention.

It will now be seen that the white work requiring more drastic washing is in bag 1 of maximum porosity, the medium colors and dye-fast work requiring less drastic washing is in bag 2 of medium mesh, and the dark or colored work requiring minimum washing is in bag 3 of fine mesh. In other words, the mesh size or porosity of the series of bags 1, 2 and 3 is graduated from large to small in accordance with the degree of washing required for the several classes of

laundry work. This avoids over-washing and reduces wear on the work.

With the foregoing in mind, it will be seen that net bag 1 of large mesh admits of a larger volume of water flow through it than through the net bag 2 of smaller porosity. Likewise, the net bag 2 permits a greater water flow and hence more washing of its contents than bag 3 of minimum or small porosity. Consequently, the porosity of the respective bag netting automatically regulates the amount of water flow and washing of the laundry therein, which is to say that this new method, among other things, relates to classifying the work according to bag porosity.

The bags of classified soiled laundry are now thrown into one washing machine, tumbled and washed by agitation therein as usual, with the result that the graduated porosity automatically regulates or proportions the amount of water circulation and flow through and agitation within the bags. Consequently, the different work classes heretofore requiring separate bath mix formula now may all be washed in one standard bath mix. This is true, although the bath mix formula for the soiled work in bag 1 is too strong or drastic in its cleansing power for the soiled work in bags 2 and 3, nevertheless the latter two bags of work withstand the washing process in the stronger mix and are not over-washed, since there is a reduced flow of washing liquid through said bags 2 and 3 due to their restricted porosity. The maximum and minimum porosity proportion the liquid flow through the bags in relation to the amount of washing required.

So much for the method features of the invention which may be practiced with standard type separate laundry bags (Figure 1) by adapting them to the new principles of use as explained. An explanation will now be given of the new bag member (Figure 2) also for use in carrying out the foregoing method and serving a purpose in addition thereto.

In Figure 2, there is shown a multiple-unit bag construction comprising net bag pockets or compartments 5, 6 and 7 of graduated-size mesh, as for example $\frac{1}{2}$ inch, $\frac{1}{4}$ inch, and $\frac{1}{16}$ inch, the same as the detached bags in Figure 1. These net bag pockets, if originally made in separate parts (Figure 1), are joined along their edges, as indicated at 8 and 9, in any appropriate manner, in substantially the same plane in order to spread out the compartments and present the entire area thereof to the washing liquid. They can be knitted together integrally or sewed together by a tape or other means to form the multiple-unit bag means or single bag member (Figure 2).

As shown in Figure 2, the multi-unit bag or laundry container has its several bag parts 5, 6, 7, etc., made of equal depth in order that their upper and lower edges be arranged approximately in the same plane or on a line even with each other for convenience in handling inside or outside the washing machines.

These laundry net bags (Figures 1 and 2) may be made of textile material or molded rubber or other suitable material. The multiple-unit bag (Figure 2) is new and hence not standard at this time with laundry suppliers. The bags and compartments vary in size, the larger mesh bag being larger overall than the medium-size mesh and so on. This overall size and progressive mesh relation has attained its present standard by reason of the size of the average family bundle sent to the laundry, the breakdown classes of which approximate the available bag sizes and

admit of a certain amount of tumbling and freedom of the work in the bags in order that the requisite agitation may take place in the washing machine. The net bags (Figures 1 and 2) are open at the top and may be closed by a draw cord or safety pin in the usual way.

It will be understood from the foregoing explanation, that usually the larger dimension bag 1 and its counterpart or compartment 5 are made of large-size mesh netting, followed by a reduced-size mesh for the smaller dimension bag 2 and compartment 6, while bag 3 and compartment 7 are still of smaller overall size with minimum-size mesh material.

These mesh sizes in the separated or loose bags (Figure 1) as well as the joined or combination bags (Figure 2) are merely suggestive of useful examples and are some of the standard size nets now used in laundries where the bags are entirely separate or loose and, under present practice, are distributed to various washing machines having the requisite bath formula according to the classification of work in the respective bags. However, in present-day practice the laundry merely uses net bags of one size porosity and makes no effort to classify the work in relation to net bag porosity by which to proportion and regulate the water flow through the bags, a new feature and mode of use which our quest has discovered and may be put into practice attended by many advantages.

The laundry classifications for the new multi-unit or combination bag (Figure 2) is the same as for the separate or conventional loose bags (Figure 1). The white soiled work (such as white shirts, white underwear, and white flatwork) is placed in the large-mesh compartment 5, while dyed or printed material of fast color is placed in compartment 6, and dark colored work such as socks and colored dresses and the like is placed in compartment 7.

The advantage of using the multiple-unit bag means 5, 6, 7 is that all or much of the work of each customer is kept together as a unit or in one lot during the washing operation. On the other hand, the new method when practiced with the separate or loose bags (Figure 1) means that a customer's several bags tumble and become scattered in the washer and must be located and brought together after the washer is opened and the loose bags removed. The invention affords a choice, as between the use of the conventional separate bags (Figure 1) and the multi-unit bag (Figure 2), both plans embodying the new idea of accommodating or adapting the known classification of work to a pre-selected mesh-size bag to attain the new results and economies herein disclosed.

Usually, the smaller separate bag 3, likewise the compartment 7 as its counterpart in the combination bag means, is made of dark color or black material instead of white, in order to prevent the depositing or shedding of a contrasting white lint therefrom onto the dark colored articles of laundry contained therein. The larger bags 1 and 2, also 5 and 6, are usually made of white material.

The net bagging surrounding any fugitive colors, as for example, the bag 2 or 3, as well as the bag compartment 6 or 7, which may contain colored work, acts to absorb any possible free dye or running color and prevent it from reaching the other bag 1 or compartment 5 containing the white work or passing out into the washing machine. In other words, the fine-mesh porous

netting 3 and 7 retains fugitive colors, a condition not attained where the dyed and colored work is placed in open or large mesh bags and subjected to over-washing, as in conventional practice, but corrected by this invention. It is for this reason that a customer's laundry containing colored work in medium and fine mesh bags 2 and 3, or in compartments 6 or 7, can be washed in the same washing machine and in the same water along with white work in large mesh bag 10 or compartment 5.

Instead of allotting a separate washing machine to each work class, such as whites, light colors, and dark colors, etc., the laundryman is now able to wash several or all classifications of work in the same machine. This is an important feature because it insures capacity loads in the machine and saves washing ingredients. Hence, this invention makes for economy in the washing liquid and labor because one machine can be used for several or all classes of work.

Furthermore, the invention has been evolved to fit in with present day standards of classification and equipment in order to avail of the knowledge and experience of operators in a laundry.

This invention is presented to fill a need for a useful laundry method and bag. It is understood that various modifications in construction, mode of operation and use or method, may and often do occur to those skilled in the art, especially after benefiting from the claimed features and teachings of an invention, and that this disclosure is descriptive of the principles but not limited to the present showing of the invention.

What is claimed is:

1. A method of washing soiled laundry work, which comprises classifying it into several different laundry classes, in accordance with the color and textile characteristics thereof, in relation to the amount of washing required for each class, and placing the different laundry classes into individual net bags which are graduated in mesh size, employing a bag having maximum size mesh for the laundry class requiring the maximum amount of washing, and employing bags of smaller size mesh for laundry classes requiring a less amount of washing, thereby attaining a maximum volume of washing-liquid flow through the laundry requiring maximum washing, with a reduced volume of washing-liquid flow through the laundry requiring less washing; and thereupon washing simultaneously, for an equal period of time, the several laundry classes within their respective bags and in one and the same washing machine and liquid.

2. A method of washing soiled laundry work, which comprises classifying it into several different laundry classes, in accordance with the color and textile characteristics thereof, in relation to the amount of washing required for each class, providing a series of net bags equal in number to the number of laundry classes, and placing the different laundry classes into individual net bags of the series and which are graduated in mesh size, placing the laundry class requiring a maximum amount of washing into the bag having the largest size mesh, and the laundry classes requiring a less amount of washing into the bags having the smaller sizes of mesh, thereby attaining a maximum volume of washing-liquid flow through said laundry requiring maximum washing, with a proportionately reduced washing-liquid flow through the laundry requiring less washing; and thereupon washing simultaneously, for

an equal period of time, the several laundry classes within their respective bags and in one and the same washing machine and liquid.

3. A method of washing soiled laundry work, which comprises classifying it into several different classes, in accordance with the color and textile characteristics thereof, in relation to the amount of washing required for each class, and employing a combination multi-unit laundry container comprising several joined bags of mesh construction, the mesh of each bag being graduated downwardly in size, placing the laundry class requiring the most washing into the bag having the largest size mesh, while the laundry classes requiring less washing are placed into the bags having smaller sizes of mesh, and thereupon washing simultaneously, for an equal period of time, the several laundry classes in one and the same washing machine and liquid; thereby resulting in proportioning a larger washing-liquid flow to and through the laundry requiring the most washing and proportionately reducing the flow through the other laundry to avoid over and under washing of the separate classes, and to keep the laundry of a customer together in one laundry container.

4. A bag means made of flexible material and including a mesh construction varying in size and forming a multiple-unit laundry container, comprising several individual compartments of graduated-mesh size, and of equal depth, being held together along their longitudinal side edges, in substantially the same plane, each of the several compartments being adapted to receive classified soiled laundry to be washed, the mesh size of the several compartments being progressively graduated from maximum to minimum size mesh openings, thereby proportioning the rate of circulation and volume flow of washing-liquid through the respective compartments, thus adapting the laundry of each customer to be classified and placed in accordance with its soiled conditions and laundering requirements within the respective compartments to undergo the washing operation in one and the same washing machine and in the same washing liquid for an equal period of time, and also to keep the laundry of one customer together in one unit container separately from other customers' laundry in other unit containers within the same washing machine.
